UNITED STATES PATENT OFFICE

162,154

AUTOMOTIVE VEHICLE REAR DECK LID HANDLE

Edward E. Glowacke, Royal Oak, Mich., assignor
to General Motors Corporation, Detroit, Mich.,
a corporation of Delaware

Application January 20, 1950, Serial No. 7,368

Term of patent 3½ years

(Cl. D10—8)

To all whom it may concern:

Be it known that I, Edward E. Glowacke, a citizen of the United States, being a resident of Royal Oak, State of Michigan, have invented a new, original, and ornamental design for an Automotive Vehicle Rear Deck Lid Handle, of which the following is a specification, reference being made to the accompanying drawing, forming a part thereof.

In the drawing:

Figure 1 is a front elevational view of an automotive vehicle rear deck lid handle showing my new design.

Figure 2 is a side elevational view thereof.

Figure 3 is a sectional view taken substantially on line 3—3 of Figure 1.

Figure 4 is a sectional view taken substantially on line 4—4 of Figure 2.

The characteristic features of the design reside in the portion shown in full lines.

I claim:

The ornamental design for an automotive vehicle rear deck lid handle, substantially as shown and described.

EDWARD E. GLOWACKE.
